UNITED STATES PATENT OFFICE.

JAMES M. THOMPSON, OF MILWAUKEE, WISCONSIN, ASSIGNEE TO LUTHER GRINDER MFG. CO., OF MILWAUKEE, WISCONSIN, A CORPORATION OF WISCONSIN.

GEARING.

1,182,056.

Specification of Letters Patent.

Patented May 9, 1916.

Application filed July 17, 1912. Serial No. 709,953.

To all whom it may concern:

Be it known that I, JAMES M. THOMPSON, a citizen of the United States, residing at Milwaukee, county of Milwaukee, and State 5 of Wisconsin, have invented new and useful Improvements in Gearing, of which the following is a specification.

My invention relates to improvements in grinding mechanism.

10 In a former patent dated June 6, 1911, and numbered 994,216, I have shown and described means for pivotally connecting the casing of the driving mechanism of a grinding wheel with a fixed support, whereby said 15 casing may be rotatively adjusted about a pivotal axis and the grinding wheel held at any desired angle, the principal object of such construction being to allow adjustments of the grinding wheel with its side face in 20 either a vertical or a horizontal plane.

The object of my present invention is to provide means whereby a substantially universal adjustment of the grinding wheel may be secured, rotative adjustments being possible about two axes at right angles to each other.

A further object is to provide means whereby the grinding wheel casing, or a curved member connected therewith, may be 30 socketed in a suitable fixed support, (to permit one of said adjustments), in such a manner as to provide a segmental bearing surface of considerable area, thus avoiding the vibration which is experienced in the operation of a grinding wheel where the casing is supported by an ordinary pivotal connection.

A further object of my invention is to provide means whereby the grinding wheel 40 may be adjusted in a circle transverse to that described by the handle.

In the drawing—Figure 1 is a plan view of my improved grinding wheel structure showing the grinding wheel and a portion of the 45 driving mechanism and casing in horizontal section. Fig. 2 is a front elevation, showing the casing partially in section. Fig. 3 is a sectional view, drawn on line $x-x$ of Fig. 2, showing a portion of the casing for 50 the driving gear wheel in its relation to the supporting bearing member. Fig. 4 is a front elevation, showing a modified form of construction.

Like parts are identified by the same

reference characters throughout the several 55 views.

The grinding wheel A is driven from the crank B, through the worm gear wheel C, worm D, worm shaft D', worm wheel E, worm F, and worm shaft G, the grinding wheel being fast upon the shaft G. The gear members are inclosed in a suitable casing, and that portion of the casing H, which incloses the driving worm gear C, is of a generally cylindrical form.

65 The casing member H is supported by a bearing flange I and a segmental bearing shield J, the parts I and J being preferably formed integrally and the shield J is provided with integral clamping arms K. An 70 ordinary clamping set screw M has threaded bearing in an aperture through a clamping arm L, which projects from the lower portion of the bearing flange I. At its upper end, this screw M is provided with an 75 ordinary swiveled clamping cap N, co-operating with the arms K, whereby the support, comprising the members I and J, may be clamped to a table. The periphery of the casing H is provided with a segmental flange 80 O, and the flange I is provided with outwardly projecting ears P parallel with the flange O. The flange O is provided with segmental slots Q and a clamping bolt R passes through each of these slots and 85 through one of the ears P. These bolts R are provided with thumb nuts S, whereby the ears P and flanges O may be rigidly bound together in any desired position of 90 rotative adjustment of the casing member H. 90

The casing member e, which incloses the gear wheel E, is also provided with bearings for the shaft G and has a hub e', rotatively mounted upon the tubular casing member h, which receives the worm shaft D'. The casing member h is integrally connected with the casing member H, and is provided with a flange d against which the hub e' seats. It will therefore be apparent that the casing member e and the grinding wheel member, have swiveled adjustment upon the upper end portion of the casing member h. A set screw Y is employed for locking the hub e' to the member h in any desired position of rotative adjustment. By revolving the 100 casing member h around the crank shaft B' as a center, or around any other center of revolution about which the casing mem- 105

ber H is rotatively adjustable, and by also adjusting the hub e rotatively upon the member h, I secure a substantially universal adjustment of the grinding wheel, whereby the same may be held in any desired position suitable for the grinding operation to be performed.

Referring to Fig. 4, it will be observed that the construction is substantially the same as that shown in Fig. 2, with the exception that a shield J', corresponding to the shield J in Fig. 2, also serves as the rear and side wall of the casing H'. In this construction, ears S' may be formed on the casing member H' and arranged to project through slots Q' in the over-lapping rim flange on the rear wall or shield J'. Wedge members T' extending through suitable holes in these ears S' are employed for locking the parts together in any desired position of adjustment.

When it is desired to change the adjustment, thumb nuts S are loosened and the grinding wheel casing member H rotated until the grinding wheel is adjusted at the desired angle. It is then locked in such position by means of thumb nuts S.

While I have shown and described the casing member H as having a peripheral outer surface bearing upon a flange I and locked in position by binding it against a shield A, I do not regard it as essential to my invention that this specific form of construction be followed, the form and shape of the mutually engaging bearing members being regarded as nonessential, although the specific form shown and described is preferred for grinding wheels having gear casings of the general form illustrated in the drawings. The supporting bearing member I is preferably curved in the arc of a circle described from the crank shaft axis as a center, but this is also not essential.

It will be observed that in the construction illustrated, the shaft D' is located at right angles to the crank shaft B and the shaft G is located at right angles to the shaft D' and laterally offset therefrom. By swinging the casing member e to carry the grinding wheel rearwardly to a position at right angles to that in which it is illustrated in the drawings, or parallel with the driving worm wheel C, it is obvious that the shaft G will occupy a position between the worm shaft D' and a vertical line extending through the crank shaft. The grinding wheel will thus be supported from a point as nearly above the crank shaft as possible, and as distant from the crank as is possible. In this position, rotative adjustments may be made upon the supporting bearing shield J without readjusting the casing member e upon the casing member h, except when it is desired to swing the grinding wheel toward a horizontal plane to facilitate the

application of grinding tools to the side face thereof. I therefore attach great importance to the fact that the shafts b, D' and G are located respectively at right angles to each other, and I also attach great importance to the swiveling adjustment of the casing members upon each other and the rotative adjustment of the casing member H upon its support.

I claim—

1. A grinding wheel casing structure comprising the combination of a fixed support, a casing member having rotatably adjustable connection with said support, and another casing member rotatably adjustable upon the first mentioned casing member, and adapted to swing in a different plane from that in which the first mentioned casing member swings upon said fixed support.

2. A grinding wheel casing structure comprising the combination of a fixed support, a casing member having rotatably adjustable connection with said support, and another casing member rotatably adjustable upon the first mentioned casing member, and adapted to swing in a different plane from that in which the first mentioned casing member swings upon said fixed support, together with locking devices for securing the several members in fixed relation to each other in any desired position of adjustment.

3. A grinding wheel structure comprising the combination of a fixed support, a casing member rotatively connected with said fixed support and provided with wheel driving connections, another casing member swiveled upon the first mentioned casing member about the axis of one of said driving connections, driven gear members mounted in the swiveled casing member, and means for locking said casing members to each other and to the fixed support in any desired position of adjustment.

4. The combination with a gear inclosing casing member, of a fixed support for the casing member, means for rotatively adjusting the casing member thereon, another casing member having swiveled connection with the first mentioned casing member on an axis at right angles to that about which the first mentioned casing member is adjusted upon the fixed support, and means for locking said casing members to each other and to the fixed support in any desired position of adjustment.

5. The combination with grinding wheel driving mechanism, of a rotatably adjustable casing member for the driving mechanism, a supporting clamping bracket provided with a curved bearing surface, and means for locking the part of said bracket having said bearing surface to one side face of the casing member at a plurality of points

along a curved line sufficiently distant from the axis of rotatable adjustment to securely hold the casing member in any given position of adjustment.

5 6. The combination with a gear casing having a peripherally curved bearing member, of a fixed support provided with a table engaging clamp and having a bearing member adapted to fit the casing bearing, 10 and means for locking said bearing member and casing together.

7. The combination with a cylindrical casing member for grinding wheel driving mechanism, of a curved bearing member 15 adapted to fit the periphery of said casing member and having a portion adapted to bear against the side wall of said casing member, and means for securing the casing member to said bearing member.

20 8. The combination with a casing member adapted to support the driving mechanism of a grinding wheel and having a cylindrically curved outer surface provided with a curved projecting rib, a curved bearing member adapted to receive the outer surface of the casing member, and clamping projections on the curved bearing member adapted to engage said rib.

9. The combination with a grinding wheel 30 casing, of a driving crank, motion transmitting connections, and a pair of casing members inclosing said motion transmitting

connections, one of said casing members being offset from the other in a direction to support a grinding wheel at a point distant from the circle described by the crank. 35

10. The combination with a grinding wheel casing, of a driving crank shaft, a worm wheel mounted thereon, a motion transmitting worm shaft at right angles to 40 the crank shaft, a worm wheel mounted on said transmitting shaft, another worm shaft driven by said last mentioned worm wheel adapted to support a grinding wheel, and casing members inclosing said worm wheel 45 and shafts and supporting the grinding wheel shaft with its wheel receiving outer end at a point distant from the plane in which the crank revolves.

11. The combination with a grinding 50 wheel casing, of a driving crank and motion transmitting connections therefor, and a pair of casing members inclosing said motion transmitting connections; one of said casing members being mounted for rotative 55 adjustment upon the other in a plane transverse to that in which the driving crank rotates.

In testimony whereof I affix my signature in the presence of two witnesses.

JAMES M. THOMPSON.
